UNITED STATES PATENT OFFICE.

FRANK LOMBARD, OF HARTFORD, CONNECTICUT.

DROP-HAMMER.

SPECIFICATION forming part of Letters Patent No. 576,273, dated February 2, 1897.

Application filed October 6, 1896. Serial No. 608,019. (No model.)

To all whom it may concern:

Be it known that I, FRANK LOMBARD, a citizen of the United States, residing at Hartford, in the county of Hartford and State of Connecticut, have invented certain new and useful Improvements in Drop-Hammers, of which the following is a specification.

My invention relates to drop-hammers of the class in which the hammer is lifted by the frictional contact of driving-rolls engaging a lifting-board; and it has for its object to provide improved means for clutching the friction-rolls in engagement with the lifting-board.

15 The improvement consists in the novel screw mechanisms for forcing the friction-rolls into contact with the board, and in the combination, arrangement, and construction of parts, as hereinafter more fully described, 20 and particularly recited in the claims.

In the accompanying drawings, forming a part of this specification, Figure 1 is a front elevation of the upper part of a drop-hammer embodying my improvements, and Fig. 2 is 25 a side view of the same. Fig. 3 is a horizontal section on the line X X of Fig. 2, and Fig. 4 is plan view of the machine with the trip-rod and clutching-lever removed. Fig. 5 is a vertical section on the line y y, Fig. 3.

30 Referring to the drawings, A designates the uprights or frame of the drop-hammer, which are adapted to support the head B, secured thereto in any well-known or suitable manner. To vertical projections b' b² on the front and rear parts of the head are secured the caps D by pins d', as shown, or by any other desired means. The caps, with the head, form horizontal spaces or ways E, in which the boxes or bearings F F' of the shafts G G' 35 are arranged and adapted to slide.

The shafts support the friction-rolls H H' between the boxes, and the friction-board I, attached to the hammer J, is passed between the rolls in the usual manner. The boxes of 45 the rear rolls H' are held stationary in the ways E by means of the screws h², which are journaled in the projections b', having collars h³ h⁴ to prevent end play, and are screwed into the hubs h⁵ on the rear sides of the boxes.

50 The collar h⁴ is pinned or otherwise removably fastened on the screws to permit the as-

sembling of the screws in place, but the collar h³ is preferably formed integrally with the screw, as it receives the strain of the clutching mechanism. Said screws are adapted to 55 hold the boxes stationary and also to adjust them when required, the rotation of the screws serving to move the boxes toward or away from the friction-board.

Upon the front sides of the forward boxes 60 F are bolted the nuts f', formed with internal threads, which are preferably double, as shown. Said nuts receive the screws L, having the double threads l' l², a half-convolution of each thread being provided, as shown. 65

The screw of the left side of the machine, which is the left side of Fig. 1, has a left-hand pitch, and the screw at the right side has a reverse or right-hand pitch, as shown in Fig. 3. The shafts or cylindrical parts l³ of the 70 screws are journaled in the projections b², and collars l⁴ are integrally formed thereon and in juxtaposition to the inner sides of the projections to receive the thrust of the strain on the boxes when the rolls are in clutched 75 engagement with the friction-board.

On the outer ends of the screw-shafts l³ are secured the levers or rock-arms m, having split hubs m' keyed upon the shafts and also tightly clamped in place by the screws m², 80 passing through the flanges m³ of the hubs. Said hubs serve as collars to prevent the end play of the shafts and receive the thrust in the opposite direction from that of the collars l⁴. Thus secured against longitudinal 85 motion the rotation of the screws will move the boxes F toward or from the plane of the friction-board. As the pitch of the screws is in opposite directions and the levers m extend toward each other, the raising of the levers 90 will consequently move the boxes and friction-roll away from the opposite roll, while the downward movement of the levers will force the boxes inward and clutch the friction-roll upon the friction-board. 95

To the front side of the machine, on one of the uprights, suitable bearings n are secured, in which is guided a vertical trip-rod R, having its upper end formed in a leaf or web r' in juxtaposition to the ends of the levers m. 100 Pins r² are riveted therein and received in slots m⁴ in the ends of the levers m. An ad-

justable dog T is secured on the trip-rod, projecting into the plane of the hammer, and thereby adapted to lift the rod by the upward movement of the hammer, as shown. The 5 hammer is provided with the usual catch t' for being held at the upward limit of its travel by engagement with the ordinary latch or pawl u, pivoted to the upright in the usual manner. The parts of the clutching mechanism are shown in the position intermediate of the limits of their travel in all the drawings.

Constructed as above described and shown, the operation of my improved clutching mechanism is as follows: By means of its weight 15 the trip-rod R, when unsupported by any mechanism and free to drop, will swing the levers m downward by engagement of the pins r² with the slots m⁴ in the ends of the levers. Such vibration of the levers will partially rotate the screw-shafts l³, which, being secured against end play by the collars l⁴ and hubs m', will therefore, by turning in the nuts f', force the boxes F inward toward the opposite boxes, thereby carrying the friction-roll H inward and thus clamping the friction or lifting board I between the rolls. The revolutions of the rolls by their driving-pulleys will lift the board and hammer until the hammer engages the dog T and lifts the trip-rod, 25 as shown in the figures. The lifting of the trip-rod turns the screw-shafts l³ in the direction opposite to that which takes place on the fall of the rod, and consequently screws the boxes F outward and removes the friction-roll from contact with the lifting-board, thus 30 allowing the hammer to fall when permitted by withdrawal of the latch u from under the catch t' in the ordinary operation of machines of this class.

40 The mechanism whereby the movement of the hammer, its blows, and its automatic or independent actions are controlled, and treadle mechanism, forms no part of this invention, and here requires neither to be shown nor described. These mechanisms may be of any 45 well-known or usual design.

The clamping action of this improved mechanism is very powerful, and the friction due to the large surfaces of eccentric and similar 50 devices is avoided. The thrust due to the clutching strain is received upon the collar l⁴, which is an integral part of the shaft, and therefore the parts cannot become displaced or out of order. The only strain received 55 upon the hubs m' tending to slip them endwise is that caused by the mere friction of the boxes in being pulled outward away from the opposite boxes by the screws L.

All the parts of the head and the clutching 60 mechanism are of suitable design, cheap in construction, and very strong and durable, and may be readily assembled or taken apart, but are not liable to become out of order or to shake loose.

I claim as my invention and desire to secure 65 by Letters Patent—

1. In drop-hammers, the combination of the head or frame, a hammer and friction-board, a pair of friction-rolls, boxes supporting the shafts of the rolls, and mounted in the head 70 or frame, one of said rolls and its boxes being movable horizontally in the frame, a pair of screw-shafts journaled in the frame or head secured against end play therein, and having their inner ends screw-threaded, nuts formed 75 or secured upon the boxes, having the threaded ends of the screw-shafts screwed therein, levers secured upon the ends of the screw-shafts, a trip-rod mounted upon the frame, and engaging the said levers by a pin-and- 80 slot connection, whereby the vertical movement of the rod is adapted to move the friction-roll and its boxes horizontally in the head, substantially as and for the purpose specified.

2. In drop-hammers, the combination of the 85 head or frame, a hammer and friction-board, a pair of friction-rolls, boxes supporting the shafts of the rolls and mounted in the head or frame, one of said rolls and its boxes being movable horizontally in the head or frame, a 90 pair of screw-shafts journaled in the frame at right angles to the shafts of the rolls, and secured against endwise movement in their bearings, screw-threads formed upon the inner ends of the screw-shafts, each of said 95 screws having its pitch in the opposite direction to that of the other, nuts secured upon the said movable boxes and receiving the threaded ends of the screws, levers secured upon the outer ends of the screw-shafts, and 100 extending toward each other a trip-rod guided on the frame and pivoted or connected to the outer ends of said levers, and means for elevating the trip-rod by the action of the hammer, substantially as and for the purpose 105 specified.

3. In drop-hammers, the combination of the head or frame B, uprights A, hammer J and friction-board I, the boxes F, mounted in the head, and the boxes F' mounted in the head 110 and movable horizontally therein, friction-rolls having their shafts journaled in said boxes, the screw-shafts l³ journaled in the head-frame, and secured against endwise motion therein, and screw-threaded at their inner ends, the threads of each screw having their pitch opposite to that of the other, the nuts f' secured to the boxes F, the levers m secured upon the outer ends of the boxes, the trip-rod R pivoted to the ends of said levers, 115 means for elevating said trip-rod by the action of the hammer, and latch mechanism for holding the hammer in elevated position, substantially as and for the purpose specified.

FRANK LOMBARD.
